UNITED STATES PATENT OFFICE

91,972

DESIGN FOR A WALL PLAQUE OR THE LIKE

Irving V. Smith, New Haven, Conn., assignor to Sargent & Company, New Haven, Conn., a corporation of Connecticut

Application January 5, 1933, Serial No. 46,742

Term of patent 3½ years

To all whom it may concern:

Be it known that I, IRVING V. SMITH, a citizen of the United States, residing in New Haven, in the county of New Haven and State of Connecticut, have invented a new, original, and ornamental Design for Wall Plaques or the Like, of which the following is a specification when taken in connection with the accompanying drawing:

Fig. 1 is a front elevational view of a wall plaque embodying my invention;

Fig. 2 is a side elevational view of the same.
Fig. 3 is an enlarged sectional view through the plaque; and

Fig. 4 is an enlarged detail plan view of a corner of the plaque showing the border decoration.

I claim:

The ornamental design for a wall plaque or the like substantially as shown.

IRVING V. SMITH.
